INVENTOR.

David H. Green

BY *M. C. Frank*
ATTORNEY

UNITED STATES PATENT OFFICE.

DAVID H. GREEN, OF SAN FRANCISCO, CALIFORNIA.

SIGNAL.

Application filed January 9, 1923. Serial No. 611,560.

REISSUED

To all whom it may concern:

Be it known that I, DAVID H. GREEN, a citizen of the United States, residing at San Francisco, in the county of San Francisco and State of California, have invented a new and useful Signal, of which the following is a specification.

My invention relates to improvements in signals, and in particular, to that type of signal adapted chiefly for the use of the automobilist, in signifying his intentions to other drivers and pedestrians as to his direction of travel, or intention to slow down or stop.

15 The present most approved and preferred method of such signalling, is to extend the arm at various angles in a vertical plane, the angle determining the signal.

Although many mechanical, electrical and other devices are on the market that will perform the equivalent signals, they appear to be unpopular and not favorably accepted by the driving public. From this, I conclude, that the human arm signal will always rank foremost, therefore, I have confined my improvement to operate in conjunction with the human arm, the object being to enhance and emphasize the arm signals given. This I accomplish, by providing a hand-covering or glove for the hand of the signal arm, and made in conformance to my invention.

Another object is, the production of such a signal adaptable for use by traffic officers and others, who give motion and direction signals.

A further object is to render night signalling more discernible, and consequently more effective, by incorporating in my invention light-reflecting crystals or brilliants.

The accompanying sheet of drawings forming part of this specification illustrates my invention, and in which:

45 Figure 1 is a front view of it made for a left hand, and, as viewed from behind the signal arm.

Figure 2 is a side view of it.

Figure 3 is a view of the invention in use as it appears to one in the rear of the signalling vehicle.

Figure 4 is a plan of one of the brilliants, and Figure 5 is a side elevation of it, and showing in section, the holder for the brilliant and the manner of attaching the same to the glove.

Referring to the various figures: The numeral 1 represents the hand of the arm 2, and upon which is the hand-covering or glove denoted in its entirety by 3, and fastened on the hand in the usual way.

The glove may be composed of any suitable flexible material used for such purposes, such as soft leather, and made up of alternate strips 4 and 5 of white and black material respectively, or of other contrasting colors. The glove proper may be a unit of one material, and the black stripes 5 may be bands sewed thereon.

I prefer to construct the glove thumbless, as shown, to allow full and free hand movement for the steering wheel.

To the back of the glove and arranged in any effective order, I attach, preferably by sewing, as seen at 6 in Fig. 5, mounted 75 crystals or brilliants 7. These brilliants are usually of glass, having many facets and ruby tinted in structure. At 9, the underside of the brilliant is silvered for light reflecting purposes, and secured in any preferred mounting 10.

The brilliants 7 may be of the same design throughout, but of different sizes and in the nature of buttons, the fingers requiring the smaller sizes.

85 In operation, a driver desiring to signal, extends his arm as heretofore, and the black and white stripes of my invention visibly accentuates the given signals day or night, and the attached brilliants, positioned and moving at different angles, receive light rays both day and night from various sources and reflect the same in all directions. Owing to the numerous facets, reflections of varying intensities will always be discernible, and 95 this is especially true at night. The red

glitterings from my signal being the reflections of the light rays from the head lights of an approaching vehicle to the rear.

While I have thus described the preferred form of my invention, I wish to have it understood that slight changes may be made within the scope of the claim hereto attached without affecting the spirit of the invention.

I claim:

A traffic signal, comprising a thumbless glove having white and black cross-stripes positioned alternately on the entire back thereof and the same studded with colored brilliants for the purpose set forth.

In testimony whereof I affix my signature.

DAVID H. GREEN.
